EXAMINATION TABLE CRUTCH AND STIRRUP UNIT

Karl V. Stefan, Houston, Tex., assignor to Med-Equip
Company, Houston, Tex., a corporation of Texas

Filed Jan. 29, 1962, Ser. No. 68,559

Term of patent 14 years

(Cl. D83—1)

FIG. 1 is a side view illustrating the novel design for an examination table crutch and stirrup unit;

FIG. 2 is a top view showing the design for an examination table crutch and stirrup unit of my invention;

FIG. 3 is an end view on the line 3—3 of FIG. 1; and

FIG. 4 is an end view on the line 4—4 of FIG. 1.

I claim:

The ornamental design for an examination table crutch and stirrup unit, substantially as shown.
